MEANS FOR SUPPORTING THE MASKS IN
PRINTING ROLLERSFrank A. Stead, Rye, N. Y., assignor to Linotype
Corporation, a corporation of New York

Application July 26, 1941, Serial No. 404,121

5 Claims. (Cl. 95—73)

This invention relates to roller printing machines of the so-called step and repeat type commonly used in the photomechanical production of a design on a printing roller.

In accordance with one well known method of producing a design on such a roller, a positive of a unit portion of the design is created photographically on a flexible film, and after the roller has been coated with a light sensitive emulsion, the image bearing portion of the positive is brought into contact with the sensitized surface of the roller and then subjected to the action of light during which those areas of the sensitized surface underlying the opaque reproduction of the design element on the positive remain unaffected by light whereas those areas of the sensitized surface underlying the transparent areas which define the design element on the positive become affected by light. Thereafter, the image bearing portion of the positive is carried out of contact with the sensitized surface of the roller and the relative positions of the positive and roller are changed either longitudinally or circumferentially after which the image bearing portion of the positive is again brought into contact with the sensitized surface of the roller and subjected to the action of light to create a second reproduction of the design element on the sensitized surface of the roller in the form of light unaffected areas bounded by light affected areas. In like manner, additional reproductions of the design element are created along and about the sensitized roller to cover that portion thereof from which it is desired to print with reproductions of the design element. Thereafter, the coating on the roller is developed to fix those areas of the coating effected by light, and then washed to remove those areas of the coating which remained unaffected by light and which are reproductions of the design element, and finally, the roller is subjected to the action of acid to etch out the areas thus bared and so form in intaglio reproductions of the design element.

In many instances, it is desirable that the several reproductions of a design element thus created about and along the roller bear a predetermined relationship with respect to one another. For example, when it is desired to print an endless pattern, the several reproductions of the design element created about and along the roller should interfit along their edges.

While with present arrangements it is a comparatively simple matter to accurately control the required change in the relative positions of the positive and roller between the successive re-

producing operations, considerable difficulty has heretofore been experienced in bringing the image bearing portion of the positive into the exact position it must occupy on the sensitized surface

5 of the roller after such change has been made to insure that the reproduction of the design element created therefrom bears the intended predetermined relationship with the other reproductions of the design element created on the

10 roller.

In accordance with the present invention, however, the above noted as well as other difficulties are obviated by so supporting the positive that each time the image bearing portion thereof is

15 carried into and out of contact with the sensitized surface of the roller any given point thereon travels through a fixed path. Under these conditions, the only requirement necessary to insure that the reproduction of a design element cre-

20 ated about and around the sensitized surface of a roller bear an intended relationship with respect to the other reproductions is that the change which must be effected in the relative positions of the positive and the roller between suc-

25 cessive reproducing operations be accurately controlled, and as stated heretofore this requirement is easily met with present machines.

For a more complete description of the invention reference may be made to the accompanying drawings wherein the invention is shown in its preferred embodiment and by way of example. Obviously, however, many changes and variations may occur to those skilled in the art which will still be comprised within the scope of the 35 invention, and it is to be understood, therefore, that the invention is not limited to any specific form or embodiment, except in so far as such limitations are specified in the appended claims.

Referring to the drawings—
40 Figure 1 is a sectional view taken along line 1—1 of Figure 3;

Figure 2 is an end view of a machine embodying the present invention;

Figure 3 is a front view, partly in section, of the machine shown in Figure 2;

Figure 4 is a sectional view taken along line 4—4 of Figure 3;

Figure 5 is a plan view of a film carrying blanket ordinarily used with such machines;

Figure 6 is a sectional view of a portion of the film, blanket and one of the blank supporting bars which illustrates the means for connecting the blanket to the bars; and

Figure 7 is a view, partly in section, taken along line 7—7 of Figure 4.

In describing the invention, let it be assumed

that an endless design comprising alternate rows of printing and non-printing squares which join end on end is to be produced along and about the surface of a printing roller 10. As usual in such cases, in image 11 of a unit portion of the design is created photographically on a flexible film 12 which is then secured to the central portion of a flexible transparent blanket 13. Also let it be assumed that the image 11 thus created on the film 12 equals in length a third of the circumference of the roll 10 and in width a third of the length of the printing surface of the roller. Under these conditions a reproduction of the image 11 on the film 12 must be created three times about and three times along the roller 10 to form an endless design thereon. To these ends, the roller 10 after being coated with a light sensitive emulsion, is mounted on a shaft 14 journaled in opening bearings 15, 16 and it is held in axial alignment therewith by means of a pair of cone-shaped members 17, 18 inserted into its ends and secured to the shaft 14. Then the blanket 13 carrying the film 12 is positioned flatwise above the roller 10 and connected at one end to a bar 19 positioned above and on one side of the roller 10 and at its other end to a sleeve 20 mounted on a rod 65 positioned above and on the other side of the roller.

The bar 19 at ends is journaled in a pair of arms 22 pivotally mounted on a shaft 24 disposed horizontally beneath the roller 10 and in axial alignment therewith, and the rod 65 carrying the sleeve 20 is journaled at its end in a like pair of arms 23 which are also pivotally mounted on the shaft 24. The arms 22, 23 being so mounted on the shaft 10 tend to rotate thereabout and in so doing each pair tend to separate and so maintain the blanket 13 taut above the roller 10 (see Figure 4). In addition, each of the arms 22, 23 is provided with a lug 25 which extends beyond the shaft 24 in bell-crank lever fashion, and a spring 26 connected to each lug and to the arm adjacent thereto tends to rotate the arm to which it is connected about the roller and so aids in maintaining the blanket 13 taut above the roller 10. The film 12 is so positioned on the blanket 13 that its longitudinal center line $a-a$ is directly above the axis of the roller 10, and so that the blanket 13 may be adjusted laterally above the roller 10 to bring this condition about it is connected at its ends to the bar 19 and to the sleeve 20 by means of hook members 21. The blanket 13, along its ends (Figs. 5 and 6) is provided with eyelets 66 adapted to receive the curved ends of the hook members 21. The hook members 21 that are connected to the blanket 13 at one of its ends extend through the bar 19 and they are provided at their outer end with adjusting nuts 67, and the hook members 21 that are connected to the blanket 13 at its other end extend through the sleeve member 20 and the rod 65, and they too are provided at their outer end with adjusting nuts 68. The openings in the sleeve member 20, however, through which the hook members 21 extend are elongated to permit the sleeve member 20 to be rotated for limited distances about the rod 65. Adjacent each opening in the sleeve member 20 on the outer face thereof a cam surface 69 is formed, and between the cam surfaces 69 on the sides of each opening in the sleeve member 20 and the adjusting nuts 68 on the hook members 21 a cam block 70 is interposed, the arrangement of parts being such that when the sleeve

member 20 is rotated about the rod 65 the end of the blanket 13 adjacent thereto is raised or lowered with a consequent lateral displacement of the longitudinal center line $a-a$ of the film 12 with respect to the axis of the roller 10. To give a visible and calibrated indication of the displacement thus effected, the sleeve member 20 is provided with an operating handle 72 having an indicating mark 73 formed thereon, and the rod 65 is provided with an indexing plate 74 having indicating marks 75 above which the indicating mark 73 on the handle 72 travel as the sleeve member 20 is rotated. The indicating marks 75 on the plate are calibrated to accord with the displacement of the longitudinal center line $a-a$ on the film 12 as the sleeve member 20 is rotated about the rod 65. In operation, a rough adjustment in the position of the film 12 with respect to the roller 10 is effected by means of the adjustable hooks 21, and then the final adjustment to bring the longitudinal center line $a-a$ of the film 12 above the axis of the roller 10 is effected by rotating the sleeve member 20. After the film 12 has been located in desired position, the sleeve member 20 is locked by means of a clamping stud 76 which projects outwardly therefrom through a slot 77 in the indexing plate 74 and which is provided with a take-up wing nut 78.

The shaft 24 on which the arms 22, 23 are rotatably mounted is secured at its ends to a pair of blocks 27, 28 carried by a pair of rods 29, 30 slidably mounted in vertically disposed sleeve members 31, 32 which form a part of a carriage 35 by means of which the blanket 13 and the film 12 mounted thereon may be moved along the roller 10 from one fixed station to another in the manner subsequently to be described.

The shaft 24, in turn, is connected by means of an intermediate link 36 to a fore-and-aft bell-crank lever 37 pivotally mounted on a short shaft 38 carried by a pair of lugs 39, 40 which project forwardly from the front wall of the carriage 35, the arrangement of parts being such that as the bell-crank lever 37 is rocked rearwardly and forwardly about its pivotal axis, the shaft 24 carrying the arms 22, 23 is forced downwardly and upwardly to fixed stations and in a path such that its axis is always in alignment with the axis of the roller 10. When the shaft 24 reaches its upper or lower station an off-center spring 41 connected to the bell-crank lever 37 and to the lug 40 on the carriage 35 acts to hold it there in operative position.

As the shaft 24 and the arms 22, 23 move downwardly the blanket 13 carrying the film 12 also moves downwardly in flatwise condition until the image area 11 of the film 12 is brought into point contact with the sensitized surface of the roller 10. During this downward travel of the film 12 the longitudinal center line $a-a$ through the image area 11 thereon is always in alignment with the axis of the roller 10, this being true since the film 12 was originally so located and the bar 19 and sleeve member 20 carrying the blanket 13 move straight downwardly. As the shaft 24 continues to move downwardly to its lower station after the image area 11 of the film 12 has been brought into point contact with the sensitized surface of the roller 10 those portions of the image area 11 on opposite sides of its longitudinal center line $a-a$ are simultaneously and progressively brought into engagement with the sensitized surface of the

roller 10 in wrap-around fashion, and as the image area 11 on the film 12 is thus brought into engagement with the sensitized surface of the roller 10 the arms 22, 23 carrying the bar 19 and the sleeve member 20 to which the blanket 13 is secured rotate about the shaft 24 against the action of the springs 26 and against the action of gravity which tends to rotate them about the shaft 24 in the opposite direction.

After the image area 11 of the film 12 has been thus brought into contact with the sensitized surface of the roller 10 it is subjected to the action of light from any suitable source (not shown) during which a reproduction of the image 11 on the film 12 is created on the sensitized surface of the roller 10 in the manner well understood in the art.

After the reproduction of the image 11 on the film 12 has been created on the sensitized surface of the roller 10 the bell-crank lever 31 is rocked forwardly to raise the shaft 24 to its uppermost position as determined by the banking of adjusting nuts 79 carried by the slide rods 29, 30 against the lower ends of the sleeve members 31, 32. As the shaft 24 travels upwardly, gravity and the action of the springs 26 act to rotate the arms 22, 23 about the shaft 24 with the result that those portions of the image area 11 of the film 12 on opposite sides of its longitudinal center line *a-a* are progressively brought out of contact with the sensitized surface of the roller 10. This continues until the image area 11 is only in point contact with the sensitized surface of the roller 10 at which time the blanket 13 is stretched flatwise between the bar 19 and the sleeve member 20 and so prevents further rotation of the arms 21, 22. Thereafter, the bar 19 and the sleeve member 20 move straight upwardly until the shaft 24 has reached its uppermost station, and as the bar 19 and sleeve member 20 move straight upwardly the image area 11 of the film 12 is also carried straight upwardly in flatwise condition and with its longitudinal center line *a-a* still in alignment with the axis of the roller.

After the image area 11 of the film 12 has been thus carried into and out of contact with the sensitized surface of the roller 10 and a reproduction of the image 11 on the film 12 created on the sensitized surface of the roller 10, the position of the roller 10 is changed beneath the film 12 from one fixed station to another or the position of the film 12 is changed above the roller 10 from one fixed station to another, the image area 11 of the film 12 again carried into and out of contact with the sensitized surface of the roller 10 and a second reproduction of the image 11 on the film 12 is created on the sensitized surface of the roller 10. In like manner, additional reproductions of the image 11 on the film 12 are created along and about the sensitized surface of the roller 10 until the image 11 on the film 12 has been reproduced three times along and three times about the sensitized surface of the roller 10 to form an endless design. Thereafter, the coating on the roller 10 is developed to fix the light affected area, washed to remove the light unaffected areas, and finally the roller 10 is subjected to the action of acid to etch out the areas exposed by the removal of the light unaffected areas of the coating all in the manner well understood in the art.

The arrangement for moving the film 12 above the roller 10 comprises the movable carriage 35 heretofore referred to and which includes as a 75

part thereof the sleeve members, the slide rods 29, 30 mounted in said sleeve members 31, 32, the shaft 24 carried by said slide 29, 30, the arms 22, 23 mounted on the shaft 24, and the bar 19 and the sleeve member 20 to which the blanket 13 is secured. The carriage 35 is slidably mounted on the inner upstanding walls of a pair of spaced horizontally disposed U-shaped members 45, 46 which are supported on the main frame of the machine by means of a pair of beams 47, 48 and it is provided with a vertically disposed plunger 49 slidably mounted in a guide member 50 carried thereby. At its upper end, the plunger 49 is loosely connected to a short fore-and-aft lever 51 pivotally mounted on a shoulder screw 52 carried by the carriage member 35. Normally a spring 53 positioned about the plunger 49 between the guide member 50 and a collar 54 carried by the plunger 49 acts to hold the plunger 49 in a lowermost position. At its lower end, the plunger 49 is tapered to accord with a V-shaped groove cut in the upper faces of a series of stop members 55 secured, as by set screw 56, to a rail 57 carried by the inner upstanding wall of the foremost U-shaped carriage supporting member 45.

In the present case where a reproduction of the design element is to be created three times along the roller 10 three stop members 55 are positioned on the rail 57, one being positioned so that when the groove in its upper face engages the tapered lower end of the plunger 49 the carriage 35 is so positioned that the image area 11 of the film 12 on the blanket 13 is positioned directly above that end portion of the roller 10 on which it is desired to create a reproduction and the other two stop members 55 being so spaced along the rail 57 in front of the roller 10 that the distances between the centers of the V-shaped grooves are the same as the width of the image area 11 of the film 12 on the blanket 13. During the creation of the first reproduction of the design element along the roller 10, the carriage 35 is moved manually along the upstanding walls on which it rests to bring the tapered lower end of the plunger 49 above the V-shaped groove in one of the stop members 55, the plunger 49 being held in a raised position against the action of the spring 53 during this movement of the carriage 35 by means of the lever 51. Then the lever 51 is released whereupon the spring 53 acts to force the plunger 49 downwardly to position the tapered lower end thereof in the V-shaped groove and thus lock the carriage 35 in fixed position in front of the roller 10. After the first reproduction has been created along the roller 10, the plunger 49 may be raised by means of the lever 51, the carriage 35 moved manually to position the tapered lower end of the plunger 49 above the V-shaped groove in another of the blocks 55 and the lever 51 released whereupon the spring 53 will act to force the plunger 49 downwardly to position the tapered lower end thereof in the V-shaped groove. In like manner the carriage 35 may be moved and the tapered lower end of the plunger 49 located in the V-shaped groove in the remaining block 55 prior to the creation of the third reproduction of the design element along the roller 10. During this travel of the carriage 35 from one fixed station to another the blanket 13 carrying the film 12 is stretched flatwise above the roller 10 in which case the relative position of the image area 11 of the film 12 remains fixed with respect to the

carriage 35. In consequence, the reproductions created along the roller 10 will interfit along their side edges to form a continuous pattern.

To the end that the roller 10 may be turned beneath the film 12 from one fixed station to another, the shaft 14 on which the roller 10 is mounted is provided with an indexing disk 69 having a number of holes 61. In the present case where three reproductions of the design element are to be created around the roller 10 the disk 60 is provided with three holes 61 spaced 120° apart and so located that as the shaft 14 carrying the roller 10 is turned the holes 61 pass in front of a locking hole 62 formed in the bearing assembly 16 adjacent the disk 60. During the creation of the first reproduction of the design element on the roller 10 the disk 60 is locked in fixed position by means of a pin 63 inserted through one of the indexing holes 61 and into the locking hole 62. Then when the second reproduction is to be created about the roller 10, the pin 63 is removed, the shaft 14 turned until another hole in the disk 60 is brought opposite the locking hole 62 at which time the shaft 14 is again locked in fixed position. Under these conditions, when three reproductions of the design element are created about the roller 10 the edges thereof will interfit to form a continuous design.

Having thus described my invention what I claim is:

1. In a machine for creating on a sensitized roller a reproduction of a design element on the image area of a flexible film, the combination of means for supporting said roller, a pair of bars

adapted to hold said film flatwise and in spaced relation to the curved surface of said roller, and means for moving said bars in conveying and diverging fixed paths on opposite sides of said roller to carry the image area of the film into and out of contact therewith.

2. The machine set forth in claim 1 characterized in that said bars are carried by arm members pivotally mounted on a shaft positioned in axial alignment with the roller, and in that means are provided for moving said shaft towards and away from the roller in a fixed path.

3. In a machine for creating on a sensitized roller a reproduction of a design element on the image area of a flexible film, the combination of means for supporting said roller, a pair of bars adapted to hold the film flatwise and in spaced relation to the curved surface of said roller, a shaft mounted in axial alignment with said roller, a pair of arm members pivotally mounted on said shaft and to one of said bars, a second pair of arm members pivotally mounted on said shaft and to the other of said bars, and means for moving said shaft toward and away from said roller from one station to another and in a fixed path.

4. The machine set forth in claim 3 characterized in that means are provided which tend to rotate each pair of arms about the shaft in opposite directions.

5. The machine set forth in claim 3 characterized in that means are provided for holding said shaft to the fixed station to which it has been moved.
